UNITED STATES PATENT OFFICE.

EVERETT C. LEWIS, OF WOONSOCKET, RHODE ISLAND, ASSIGNOR, BY MESNE ASSIGNMENTS, TO JOHN T. UNDERWOOD, OF BROOKLYN, NEW YORK.

TYPE-WRITER ATTACHMENT.

SPECIFICATION forming part of Letters Patent No. 585,918, dated July 6, 1897.

Application filed October 28, 1896. Serial No. 610,264. (No model.)

To all whom it may concern:

Be it known that I, EVERETT C. LEWIS, a citizen of the United States, and a resident of Woonsocket, in the county of Providence and State of Rhode Island, have invented a certain new and useful Improvement in Type-Writer Attachments, of which the following is a specification.

My invention relates to that class of type-writing machines wherein a printing-sheet is interposed between the type and the platen of the machine for the purpose of producing an impression upon the paper by the action of the type.

15 My invention is an attachment to be used in connection with such type-writing machines for the purpose of sustaining and operating a printing-sheet in the field of the type, and yet so constructed as to permit of the ready introduction and removal of the printing-sheet into or out of the field of the type at the will of the operator, and my attachment may be used either with or without the removal of the printing-ribbon, as at 20 present employed in such type-writing machines, and I may employ either one or more of my attachments in combination with one type-writer machine, and I may use different colors or characters of printing-sheets with 25 each of said devices, thus giving to the operator of the machine an opportunity to select either the character or the quality of the printing-sheet which it is desirable to employ and to introduce or remove the same from 30 the field of the type with great facility and ease.

I have illustrated my invention in the accompanying drawings, designating the parts by letters and figures and referring to like 35 parts by like letters and figures.

Figure 1 is a plan view of the type-writing machine with the paper-carrying device and platen removed, showing my attachment secured to the upper side of the table of the 40 device and withdrawn from the field of the type, but in dotted lines is indicated the position of the device when moved forward into the field of the type. Fig. 2 is a vertical sectional view of Fig. 1 on the lines xx , showing,

however, another of my attachments on the 50 opposite side of the machine from the one shown in Fig. 1, and in Fig. 2 I show one of my attachments thrown forward into the field of the type and the other withdrawn therefrom. Fig. 3 is a plan view of my device 55 with a portion of the carriage broken away to show the operative mechanisms beneath the top plate thereof. Fig. 4 is a vertical section of my attachment as shown in Fig. 3. Fig. 5 is a vertical section of Fig. 4, taken on the 60 lines $x'x'$. Fig. 6 is a detailed view showing the under side of the frame or disk supporting the printing-sheet. Fig. 7 shows a plan view of the printing-sheet, and Fig. 8 is a sectional view taken on the lines x^2x^2 . 65

I have illustrated my invention in connection with the ordinary form of type-writers, such as that sold under the title of the "Remington type-writer" machine, but it may be employed with any machine wherein a printing-sheet is used in substantially the same manner. 70

In the drawings, A represents such type-writing machine as I have described.

a' is the table of the machine.

a^2 is the gang of type-bars, of which a^3 is 75 one of the levers, a^4 one of the type shown in operative position, and a^5 one of the levers leading to the bank of keys, as a^6 .

a^7 and a^8 are the spacing-levers, leading to 80 the space-bar a^8 .

a^9 and a^{10} are reels, on which are run the ink-ribbons a^{10} and a^{10} .

a^{11} and a^{12} are the apertures in the table a' , 85 through which the ribbon passes.

a^{12} and a^{13} are set-screws in the table a' for the purpose of holding in position my attachment.

a^{14} represents the platen of the machine. I have deemed it unnecessary in this connection to show the carriage in which the platen is mounted or the other operative features of the machine which are unnecessary for the purpose of illustration here. 90

I have designated my attachment, as applied to the machine, as B and B' in Fig. 2. The one indicated as B is shown in operative position in the field of the type and the one

indicated as B' is designated as not in operative position—that is to say, out of the field of the type.

I will now proceed to describe the details of the construction of my attachment. b' is a cross-bar provided with the slots 2 and 2, which are arranged to slide under the set-screws a¹² and a¹³ and to be held upon the table a' by said set-screws. Referring to Fig. 4, it will be seen that this bar b' is provided with the upturned right-angular flange b², which flange is again bent at right angles, as at b³, and on the other side of the bar b' is also provided with a flange b⁴, bent at right angles thereto, and the flange b⁵ bent at right angles to the flange b⁴, thus forming a base on which the carrier of the attachment is mounted of a width substantially equal to that of said carrier, and also providing a space for the operative mechanisms, which I call the "trigger movement" of my device, as shown in section in Fig. 5 along the lines x' x' of Fig. 4. This trigger movement of my device may be described as follows: b⁶ is a plate provided with the slots or ways b⁷ and b⁸, through which the plate b⁶ is secured to the flange b⁴ by the screws b⁹ and b¹⁰; but said screws are introduced only far enough to operate as guides for the plate b⁶, and b¹⁰ is a binding-post on the base-plate or brace b', and b⁹ is a binding-post secured to the plate b⁶. Between said binding-posts b⁹ and b¹⁰ is interposed a spiral spring b¹¹, with its tension directed to maintain the plate b⁶ in the position shown in Fig. 5. b¹² is a chain secured to the binding-post b⁹ and passing over the pulley b¹⁵ and secured to the spacing-lever a⁷ and operated by the spacing-bar a', as heretofore described.

b¹³ is a lug which is part of the plate b⁶, passing through an aperture in the plate b¹⁷, hereinafter to be described, and operating on the lever b²⁴.

b¹⁴ is a staple secured to the base-plate or brace b', and b¹⁵ is a pulley mounted on a spindle secured to said staple b¹⁴.

b¹⁶ and b¹⁷ are set-screws for the purpose of elevating or lowering the attachment with reference to its position between the type and the platen.

b¹⁷ is a plate which I prefer to call a "carrier," upon which is mounted the operative mechanisms of my device for moving the printing-sheet. It is provided with a right-angular flange b¹⁸, through which passes a thumb-screw b¹⁹, which is intended for the purpose of adjusting the throw of the device, and b²⁰ is a lock-nut to fix said throw when the same is determined by the thumb-screw b¹⁹.

b²¹ and b²² are slots in the plate b¹⁷, and b²² and b²³ are screws to hold said plate b¹⁷ to the flanges b⁵ and b³ of the base-plate b'. These screws are sufficiently loose to permit the carriage b¹⁷ to slide within the ways b²¹ and b²².

b²³ is an aperture within the plate b¹⁷ to permit the lug or trigger b¹³ to pass through the same and operate freely within said aperture.

b²⁴ and b²⁵ form a crank-lever pivoted at

b²⁵, said crank-arm b²⁶ being pivotally connected with the lever b²⁷, which is provided at the other end with the pawl b²⁸, and the guide b²⁹ is interposed to hold said lever b²⁷ in position.

b³⁰ is a lug secured to the plate b⁷, and b³¹ is a knife-spring secured to the binding-post b³², bearing on the lever b²⁴ at the point b³³, 75 retaining the same against the post b³⁰. The lever b²⁴ is provided with the aperture b³⁴ to permit the lug or trigger b¹³, when my attachment is withdrawn from operative position, to respond to the movement of the space-bar 80 without operating my attachment.

b³⁵ is a ratchet-wheel secured to the spindle b³⁶, which passes through a journal-bearing in the plate b¹⁷. b³⁷ is a metal disk employed to support the printing-disk. In Fig. 6 I 85 have shown a view of this disk, looking at the same from the under side, where it will be seen that a space is provided b³⁸ and b³⁹, which is intended as an opening or aperture through which the type may act upon the 90 printing-sheet. This disk b³⁷ is secured to the under side of the plate b¹⁷ by the screws x³ and x⁴.

b³⁹ is a locking-lever, preferably of a knife-spring metal, hinged at b⁴⁰ and provided with an indenture or notch b⁴¹. The open position of the locking-lever b³⁹ is also shown in dotted lines.

b⁴² is the printing-sheet as the same appears through the aperture b³⁸ in the disk b³⁷. In 100 Fig. 7 I have shown this printing-disk, which is mounted on a friction-button b⁴³, said friction-button having an aperture x⁴ of a size to make frictional contact with the spindle b³⁶.

In Fig. 8 I have shown a sectional view of 105 the spindle b³⁶, the ratchet-wheel b³⁵, the carriage-plate b¹⁷, the button b⁴³, the printing-disk b⁴², the sustaining-disk b³⁷, and the locking-lever b³⁹. I have shown these parts separated and in position to be run together, and 110 it will be noted that the spindle b³⁶ is provided at one end with an annular indenture or groove b⁴⁴. It is intended that the notch b⁴¹ of the locking-lever b³⁹ shall slip into this annular notch b⁴⁴ when the parts last referred 115 to are run upon the spindle b³⁶ and hold the same in position together.

The operation of my device is as follows: I introduce the printing-sheet b⁴² between the disk b³⁷ and the carrier b¹⁷ by first releasing 120 the locking-lever b³⁹ from the annular aperture b⁴⁴ and withdraw the spindle b³⁶, carrying the ratchet-wheel b³⁵. I then introduce between the disk b³⁷ and the carrier b¹⁷ the printing-sheet b⁴² and again introduce the spindle 125 b³⁶ through said printing-disk and through the supporting-disk b³⁷ and cause the locking-lever b³⁹ to move in a position shown in Fig. 6, thus locking together the parts indicated. The friction-button b⁴³, as heretofore stated, 130 has a central aperture x⁴, which makes frictional contact with the spindle b³⁶. It will be manifest, therefore, that said printing-disk will be carried by said spindle and the button

b^{43} is of sufficient thickness to separate the supporting-disk b^{37} and the under side of the carrier b^{17} , thus permitting the printing-disk to move freely between said supporting-disk 5 and carrier with the movement of the spindle b^{36} and the ratchet-wheel b^{35} .

It will be understood that I present to the paper to be impressed that side of the printing-sheet which is most favorable for the 10 transmission of the ink to the paper. I then secure my attachment to the table of the type-writer by the screws a^{12} and a^{12} , passing into the slots 2 and 2. I may partially adjust the same in these slots, so as to bring the attachment 15 in the right position. I so adjust my attachment with reference to the operative field of the type that when the device is drawn back in the position shown in Fig. 1 the printing-disk will be out of the field of the type, 20 and when it is thrown forward, as in my attachment B in Fig. 2, the printing-disk will be within the field of the type. This adjustment may be facilitated by the operation of the thumb-screw b^{19} and the set-screw b^{20} . I 25 find this adjusting device also convenient when it is desired to shift the printing-surface of the printing-sheet, so as to bring a new surface into operation when one surface is partially exhausted. I then secure the chain 30 b^{12} to one of the spacing-levers connected with the spacing-bars, as a^7 . When my attachment is thrust forward—that is to say, when the carriage b^{17} is caused to move in the slots b^{21} and b^{21} into the position shown in Fig. 3—the trigger b^{18} is in position to engage the crank-lever b^{24} , and with the operation of the space-bar from time to time as the type-writer is operated the plate b^6 , carrying said trigger b^{18} , is caused to reciprocate first in the power 35 40 of the spacing-bar and it is then retracted by the spiral spring b^{11} . With the movement of said plate and trigger in the power of said spacing-bar said trigger b^{18} engages the crank-lever b^{24} and causes the pawl b^{29} to engage the ratchet-wheel b^{35} , thus moving the printing-disk one step and thus presenting to the type 45 a fresh printing-surface. When, however, the carrier b^{17} is retracted into the position shown in Fig. 1, the trigger b^{18} , responding to 50 the movement of the space-bar, moves within the slot b^{34} of the lever b^{24} . Thus the movement of said trigger during the period that the carrier b^{17} is withdrawn is an idle movement—that is to say, it does not affect the lever b^{24} , and therefore the printing-disk is 55 stationary.

I may employ my device either singly or duplicate—singly, as shown in Fig. 1, and duplicate, as shown in Fig. 2—or I may use either 60 one or two attachments in association with the ordinary inking-ribbon of a type-writer or without such ribbon, as convenience may dictate. The advantage of using several printing-sheets is that I may employ printing-sheets 65 of different colors or having different qualities—that is to say, some printing-sheets are prepared with inks or coloring-matters

that will duplicate in an ordinary letter-copying book, while others have the quality of being indelible and not capable of copying. 70 With the ordinary arrangement of the type-writer ribbon it is necessary, when it is desired to use a copying-ribbon or non-copying ink or to introduce a new color, either to reel off the copying-ribbon and introduce another or 75 to carry two on the reels, thus necessitating the winding and the unwinding of the reel with each change.

My device is intended to provide a convenient means of rapidly changing the printing-sheet and readily introducing another. Moreover, in the ordinary printing-ribbon only a limited part of the ribbon—that is to say, usually the center thereof—is brought into the field of the type, whereas with the arrangement that I have shown by the adjustment of the thumb-screw b^{19} I may bring substantially the whole of the printing-surface of the disk employed into the field of the type. Moreover, these disks may be introduced and removed with great readiness and facility. Furthermore, I may use a disk made of materials which could not be used as an ink-ribbon because of their lack of tensile strength. 85

Furthermore, my attachment is capable of 90 very convenient economical use in connection with what is known as the "mimeograph" process of duplicating type-written matter. As the mimeograph process is at present operated, the ink-ribbon is first removed. Under 95 the present arrangement of type-writers this requires the unreeling of the ribbon and the removal of the same from the field of the type, for it is necessary in that process to bring the type directly in contact with the wax sheet 100 from which it is desired to make a stencil. 105

In the operation of my device all that is necessary is to withdraw the carrier of the attachment, so as to remove the printing-sheet from the field of the type. This done, the 110 machine is ready to receive the wax sheet which is employed in the preparation of the stencil used in what is known as the "mimeograph" process.

I may employ as the printing-sheet to be 115 used as my attachment any of the well-known printing-sheets which may be used for this purpose; but I prefer to use a thin paper, as this is more economical.

What I claim is—

1. In a type-writing machine the combination with the type and platen, of an inking-sheet suitably mounted on a reciprocating carrier to move said sheet into and out of the operative field of the type, substantially as 125 described.

2. In a type-writing machine the combination with the type and platen, of an inking-disk suitably mounted on a reciprocating carrier, to move said disk into and out of the 130 operative field of the type, and means operated by the movement of the type-writing machine, to rotate said disk, substantially as described.

3. In a type-writing machine, the combination with the platen, of an inking-disk suitably mounted on a reciprocating carrier to move said disk into and out of the operative field of the type, and means operated by the movement of the type-writing space-bar to rotate said disk, substantially as described.

4. In a type-writing machine the combination with the type and platen, of an inking-disk suitably mounted on a reciprocating carrier to move said disk into and out of the operative field of the type, said disk being secured to the carrier by a spindle having at one end a ratchet-wheel, with a pawl for said ratchet, and a trigger engaging said pawl, operated by the movement of the machine to rotate said disk, substantially as described.

5. In a type-writing machine the combination with the type and platen, of an inking-disk suitably mounted on a reciprocating carrier, to move said disk into and out of the operative field of the type, said disk being mounted on said carrier by means of a spindle, having at one end a ratchet-wheel, with a pawl for said ratchet, and a trigger engag-

ing said pawl while the disk is in the field of the type, said trigger being operated by the movement of the machine, substantially as described.

6. In a type-writing machine the combination with the type and platen, of an inking-disk suitably mounted on a carrier, said carrier being mounted to reciprocate on a frame secured to the top plate of the type-writer machine, at either side thereof, to move the disk into and out of the operative field of the type, said disk being mounted on said carrier by means of a spindle having at one end a ratchet-wheel with a pawl for said ratchet, and a trigger engaging said pawl while the disk is in the field of the type, said trigger being operated by the movement of the space-bar, substantially as described.

Signed at Woonsocket, in the county of Providence and State of Rhode Island, this 22d day of October, A. D. 1896.
